CARAFE OR THE LIKE

Ronald G. De Puy, Corning, N.Y., assignor to Corning
Glass Works, Corning, N.Y.

Filed July 30, 1970, Ser. No. 24,221

Term of patent 14 years

Int. Cl. D7—01

U.S. Cl. D44—21

Fig. 1

Fig. 2

Fig. 3

Fig. 4

Fig. 5

FIG. 1 is a side elevational view of a carafe or the like embodying my new design, with the opposite side being a mirror image.

FIG. 2 is a top plan view.

FIG. 3 is a front elevational view.

FIG. 4 is a rear elevational view.

FIG. 5 is a bottom plan view.

I claim:

The ornamental design for a carafe or the like, as shown and described.
